UNITED STATES PATENT OFFICE.

EDWARD SCHWARTZ, OF CHICAGO, ILLINOIS, ASSIGNOR TO PELOUZE MANUFACTURING COMPANY, OF CHICAGO, ILLINOIS, A CORPORATION OF ILLINOIS.

QUICK-BREAK ELECTRIC SWITCH.

1,149,409.

Specification of Letters Patent.

Patented Aug. 10, 1915.

Application filed March 23, 1912. Serial No. 685,879.

To all whom it may concern:

Be it known that I, EDWARD SCHWARTZ, a citizen of the United States, residing at Chicago, Cook county, and State of Illinois, have invented and discovered certain new and useful Improvements in Quick-Break Electric Switches, of which the following is a specification.

My invention relates to electric switches and its object is to provide a device of this class adapted to insure a jump or snap action of the contacts as they are separated or brought together for the purpose of preventing arcing and the invention particularly relates to devices in which the contact members themselves are composed of rigid pieces and are therefore not capable of obtaining the spring snap action in and by themselves.

To this end my invention is embodied in preferable form in the device hereinafter described and lettered in the accompanying drawings.

In this application the invention is disclosed as embodied in a mechanism adapted to be applied to the switch plug of an electrically heated iron but it is obvious that the invention is adapted for use in connection with other appliances and for other purposes.

In the accompanying drawings which illustrate the invention Figure 1 is a side view in elevation of an electrically heated iron showing the switch plug in circuit closing position; Fig. 2 is a plan view of the iron with the handle and the switch plug both removed; Fig. 3 is a bottom plan view of the switch plug or block; Fig. 4 is a plan view looking up and partly in horizontal section of the switch plug or block and the other mechanism on the iron constituting in connection with said switch plug the features of my invention and in which view the plug is shown in circuit closing position; Fig. 5 is a similar view showing the switch plug in circuit breaking position; Fig. 6 is a vertical transverse section on the line 6—6 of Fig. 4; Fig. 7 is a vertical longitudinal section on the line 7—7 of Fig. 4 and looking in the direction indicated by the arrow in Fig. 4; Fig. 8 is an outer end view of the iron with the switch plug or block removed and Fig. 9 is an inner end view of the switch plug or block.

Referring to the drawings 1 is the main

body portion of the iron to which may be secured by suitable attaching means, the ironing plate 2 and the resistance-carrying member 3. This latter member may be provided with a suitable resistance coil of any suitable character adapted to be electrically connected to rigid contact members 4 mounted on the main body portion 1 and rising vertically therefrom. Adapted to cooperate with these contact members 4, in order to close or open the circuit through the same and thereby through the resistance carried by the iron, are two pairs of contact members 5—5 of which each pair is adapted to embrace one of the contact members 4 when the members are adjusted to circuit closing position. Each pair of contact members 5 is mounted in a slot 6, extending longitudinally of a switch plug or block 7 made of non-conducting material and provided with a knob 8, whereby it may be manually grasped and operated. This switch plug is provided on its under surface with a metallic plate 9, which has flanges 10 extending along the outer longitudinal edges of the plug, which flanges are turned upwardly slightly outside of the plug and are adapted to engage longitudinal grooves 11, formed in the body portion 1 of the iron. By this arrangement the plug is adapted to be slid in and out in the grooves and toward and away from the contact members 4. The grooves or slots 11 are open at their outer ends, thus permitting the plug to be readily applied to the iron and readily removed therefrom.

On the under surface of the plug there is provided a combined holding and snap member 12, consisting of a tongue projecting inwardly of the plug and preferably formed by bending a strip integral with the plate 10 upwardly and back down to a position parallel with the surface of the plate. The end of the tongue is secured to the plate by means of a pin 13, or similar means of attachment. This member has an inclined head, 14, at its forward or inner end, preferably of an arrow shape to provide two inclines with abrupt shoulders 15, at the rear ends of the inclines. From the rear end of the arrowhead, the member is inclined at 16 laterally of the line of movement of the plug on each edge of the member. These inclines terminate in opposite abrupt shoulders or cam projections 17. From these

shoulders the members are again inclined on each side thereof at 18, to near the end thereof. At the outer end of the member the same is provided with a stop heel, 19, formed by projections extending laterally from the tongue. This tongue member is adapted to coöperate with a spring 20 fixed on the main portion 1, in order to give a jump or snap action to the plug at the instant that the contacts are brought into closing position or carried out of such position for the purpose of preventing arcing of the contacts. The spring 20 is preferably a stiff flat spring and it is provided with an attaching base 21, a rigid base arm 22 and with converging, yielding, arms 23. The arms 23 converge closely together near the rear ends thereof and at this point are provided with inwardly bent shoulders or loops 24 which approach one another and form a narrow throat adapted to coöperate with the arrowhead 14, and with the abrupt projections 17 of the tongue member on the block or plug. To the rear of the bends or shoulders 24, the spring arms are extended into entrance arms 25, provided with slight inward bends 26 and with diverging ends. In the application and operation of the device, the flanges 10 are inserted into the slots or grooves 11 and the plug pushed inwardly. The arrow shaped head of the tongue of the plug will first engage the ends of the spring arms, the divergence of which will permit the ready entrance of the head and the pressure of the head will force the arms slightly apart and when the shoulders of the arrow reach the throat they will, under a greater resistance due to the greater inward projection of the shoulders 24 of the spring arms and the greater rigidity of the arms at this point, force the arms sufficiently apart to permit the arrowhead to move past the same. As the head moves past these bends or shoulders, the arms spring against the sides of the tongue and serve to retain the plug in position. In this position of the plug which is shown in Fig. 5, the tongue will be firmly gripped by the spring arms behind the head and the plug thus prevented from withdrawal except by the exertion of considerable force in an outward direction upon the plug, sufficient to carry the arrowhead outwardly beyond the bends or shoulders of the arms. In this position, the contact members will be out of engagement and the circuit broken. To close the circuit, the plug is pushed in still farther, whereupon the incline 16 will ride against the shoulders or bends of the arms, gradually forcing the arms apart until the abrupt projections 17, of the tongue, are brought into alinement with the abrupt projections afforded by the bends of the spring arms. On the continued pressure against the plug, the projections 17 will snap past

the bends of the arms, the spring action of such bends serving to give the tongue and consequently the plug, a quick, forward, automatic movement, which throws the contacts on the plug into circuit closing engagement with the fixed contacts on the body portion, thus establishing the circuit by a quick, automatic jump action, which will serve to prevent any danger of arcing between the contacts. The heel portion 19, of the tongue, in this inward movement of the plug to establish the closing of the circuit, is carried against the outer faces of the bends of the spring arms, so as to thereby limit the inward movement of the plug.

Figs. 4 and 5 show the plug in closing position.

An outward pressure or pull on the plug, for the purpose of breaking the circuit, carries the inclines 18 against the shoulders or bends of the spring arms and when the shoulders or cams 17 reach said bends, they will be caused to snap or jump past the bends and thus automatically and quickly carry the movable contacts out of circuit closing position, thus breaking the circuit without danger of arcing. The removal of the plug from the iron or other device to which it may be applied, may be effected by the exertion of a considerable force applied outwardly against or upon the plug, sufficient to carry the arrowhead beyond the bend or shoulders of the spring arms.

Having thus described my invention, what I claim is—

1. In an electric switch, the combination with a fixed contact member of a sliding block, a second contact member carried by said block, a non-conducting spring fixed relatively to said block and having an abrupt shoulder projecting laterally of the line of movement of the block and a spring-engaging member carried by said block and having an abrupt projection extending transversely of the line of movement of the block and in line with the projection in said spring, substantially as described.

2. In an electric switch, the combination with a fixed contact member of a movable switch plug, a second contact member carried by said switch plug, a member having converging spring arms, a member carried by the plug and adapted to engage said spring arms, said arms having gripping portions, means on said plug member to engage said gripping portions to hold the plug in place but in circuit breaking position and means on said member to engage said gripping portions to hold the plug in circuit closing position, substantially as described.

3. In an electric switch, the combination with a fixed contact member, a supporting device therefor, a movable contact member, a switch plug carrying the latter, a spring carried by the supporting device and hav-

ing converging spring arms, a spring engaging member carried by the plug, said latter member being provided with means operable to be gripped by said arms to retain the plug in place on the supporting device and with means operable to be urged by the arms to effect an automatic snap action of the plug, substantially as described.

10 4. In an electric switch, the combination with a supporting body of a contact member thereon, a slideable switch plug, a contact member on said plug, a spring fixed on said body and having converging arms forming a throat and said arms having abrupt approaching bends at said throat, a spring engaging member carried by said plug and having an arrow shaped head at one end thereof and with inclines meeting 20 at a central abrupt shoulder operable to engage and be snapped past said spring shoulders as the plug is moved in or out, substantially as described.

5. In an electric switch, the combination with a supporting body of a contact member carried thereby, a removable sliding switch plug having means to engage said body, a non-conducting spring fixed in said body and having separated yielding arms, said arms being provided with opposite lateral bends extending toward one another, a contact member carried by said plug, a non-conducting member carried by said plug and having a laterally projecting head adapted to be gripped by said spring bends and having cam surfaces to the rear of said head for engagement by said bends, substantially as described.

In witness whereof, I have hereunto set my hand and seal at Chicago, Illinois, this 2nd day of March, A. D. nineteen hundred and twelve.

EDWARD SCHWARTZ. [L.S.]
